DESIGN FOR A SHOE

Nathan H. Gilman, New York, N. Y.

Application March 8, 1938, Serial No. 75,674

Term of patent 3½ years

To all whom it may concern:

Be it known that I, Nathan H. Gilman, a citizen of the United States of America, residing in the city of New York, county of New York, and State of New York, have invented a new, original, and ornamental Design for a Shoe, of which the following is a specification, reference being had to the accompanying drawing, forming part thereof.

Fig. 1 is a plan view of a shoe embodying my new design.

Fig. 2 is a side elevational view thereof.

I claim:

The ornamental design for a shoe substantially as shown.

NATHAN H. GILMAN.
